Primary Examiner—Ted Shooman*Assistant Examiner*—Cheri Cohen*Attorney, Agent, or Firm*—Robert R. Keegan; Head & Johnson**[57] CLAIM**

The design for a combined golf tee and placement tool, as shown and described.

DESCRIPTION

FIG. 1 is a top plan view of a combined golf tee and placement tool showing my new design, the opposite view being a mirror image;

FIG. 2 is a front end elevational view thereof;

FIG. 3 is a rear end elevational view, partially broken away for clarity of illustration; and,

FIG. 4 is a side elevational view thereof, the opposite side being a mirror image.
